UNITED STATES PATENT OFFICE.

LANSON B. JOYNER, OF WASHINGTON, LOUISIANA.

INTERNAL-COMBUSTION ENGINE.

1,391,832.

Specification of Letters Patent. Patented Sept. 27, 1921.

Application filed March 29, 1920. Serial No. 369,762.

To all whom it may concern:

Be it known that I, LANSON B. JOYNER, a citizen of the United States, and a resident of Washington, in the parish of St. Landry and State of Louisiana, have invented a new and useful Improvement in Internal-Combustion Engines, of which the following is a full, clear, and exact description.

My invention relates to improvements in internal combustion engines, and it consists in the combinations, constructions and arrangements herein described and claimed.

An object of my invention is to provide an improvement over the device covered by Patent No. 1,275,264, issued to me August 13, 1918, said improvements consisting in the provision of more efficient and satisfactory means for cooling the pistons and parts associated therewith and for reciprocating the pistons within the cylinders.

A further object of my invention is to provide in a device of the type described a novel form of valve operating mechanism.

Other objects and advantages will appear in the following specification, and the novel features of the invention will be particularly pointed out in the appended claims.

My invention is illustrated in the accompanying drawings, forming part of this application, in which—

Figure 1 is a side elevation illustrating my invention,

Fig. 2 is a plan view of the device partly broken away and in section,

Fig. 3 is a section along the line 3—3 of Fig. 2,

Fig. 4 is an end view of a portion of the device,

Fig. 5 is a side view of a fragmentary portion of the device,

Fig. 6 is an enlarged sectional view of a portion of the device,

Fig. 7 is a section along the line 7—7 of Fig. 2.

In carrying out my invention, I provide a base 1 carrying a supporting frame 2 upon which are mounted two horizontally disposed co-axially aligned similar cylinders 3 and 4. A crank shaft 5 is journaled at 6 in one end of the frame 2. A fly wheel 7 is rigidly secured to each end of the crank shaft 5.

A piston 9 is mounted upon a piston rod 8 to reciprocate within each of the cylinders 3 and 4. The piston rod 8 extends through

both cylinders and is secured within an elbow member 74 which is formed integrally with a cross head 10. The latter is connected by a pitman 11 to a crank 12 upon the crank shaft 5.

A gear 13 keyed to an end of the crank shaft 5 meshes with a gear 14 which is rigidly secured to a stub shaft 15. The latter is journaled in brackets 16 which are secured to a side of the frame 2. The gear 14 is in mesh with a gear 17 which is carried upon a cam shaft 18. The latter is journaled in a bracket box 19, which is secured to the side of the frame 2 adjacent one end, and in auxiliary bracket boxes 20 which are secured to the frame 2 adjacent the ends of the cylinders 3 and 4. A laterally extending housing 21 is formed integrally with each of the cylinders 3 and 4 at each end thereof or may be secured thereto in any approved manner. The housing 21 has an upper valve chamber 22 communicating with an intake manifold 23 and a lower valve chamber 24 communicating with an exhaust manifold 25.

An intake valve 26 is seated within an opening between the upper valve chamber 22 and a combustion chamber 27. The combustion chamber 27 communicates with the interior of the cylinder 3 (see Fig. 7). A vertically disposed stem 29 connects with the valve 26 and carries a disk 31 at its upper end. A compression spring 30 arranged between the disk 31 and the housing 21 tends to maintain the valve 26 in its closed condition. Likewise, a spring 33 arranged between a disk 34 carried upon the lower end of a stem 32 which connects with the exhaust valve 28 tends to normally maintain the latter in its closed condition.

A rocker arm 35 is pivoted at 36 to a support 37 which is secured by the housing 21 (see Fig. 3). The rocker arm 35 carries a roller 35' at one end and this roller is arranged to constantly bear against the end of the stem 29. The rocker arm 35 is connected at its other end to a rod 38. The latter is slidably disposed in a sleeve 39 which is formed integrally with the housing 21. The end of the rod 38 projects below the sleeve 39 and presses against a cam member 40 on the cam shaft 18. A second rocker arm 41 which is pivoted at 42 to the bracket box 20 carries a roller 41' at an end and this roller is arranged to constantly bear against the end of the stem 32. A roller 43 is carried at

the other end of the rocker arm 41 and is in contact with a cam member 44 which is on the cam shaft 18.

A carbureter 45, which is controlled and operated in any approved manner, communicates with the intake manifold 23, as clearly shown in Fig. 1 of the accompanying drawings. A spark plug 46 is arranged within each of the housings 21 and projects within the combustion chamber 27. Each spark plug 46 is connected to a magneto 47 which is operated by a stub shaft 48. The latter is driven by the cam shaft 18 by means of a sprocket 51 keyed to the cam shaft, a sprocket 49 keyed to the stub shaft 48 and the chain 50.

It will be understood that the construction of the parts within the housings 21 which are located at each end of each of the cylinders 3 and 4 is identical. The cam members 40 and 44 are arranged upon the cam shaft 18 so that alternate inlet valves 26 and exhaust valves 28 will be actuated simultaneously.

In order to properly cool the pistons and the parts associated therewith, I provide a pump 52 which is of the rotary type and is operated by the stub shaft 48. An inlet pipe 53 connects the pump with a source of water supply (not shown). A supply pipe 54 extends downwardly and then rearwardly from the pump, as shown in Fig. 1. This pipe 54, upon reaching the rear end of the device, extends upwardly and then forwardly, as shown in Fig. 5. The pipe 54 has a flanged terminus 55. The end of the piston rod 8 is slidably disposed within the pipe 54, as best seen in Fig. 5. The piston rod 8 is formed with a central bore 68 extending the entire length thereof. I provide packing glands 56 at the ends of the cylinders 3 and 4. A length of pipe 57 connects the packing glands 56 located at adjacent ends of the cylinders 3 and 4. It will be understood that the piston rod 8 extends through the packing glands 56 and the intermediate pipe or casing 57. Each of the cylinders 3 and 4 is fashioned with cylinder heads 58 and 59. The construction of the packing glands 56 is best seen in Fig. 6 of the accompanying drawings.

It will be noted that the packing gland casing consists of two similar semi-cylindrical members 62 having lateral lugs 62 secured together by bolts 73. Outer packing rings 63 are disposed in co-operating internal semi-annular recesses 63' which are formed in the walls of the semi-cylindrical members 62. A plurality of relatively thin inner rings 63" have their walls disposed between the outer packing ring 63 and the piston rod 8. The outer piston rings 63 are preferably formed of cast iron or the like, while the inner piston rings 63" are preferably formed of brass or a like com-

position. An internal semi-annular recess 65 in each semi-cylindrical member 62 near an end co-operates with the semi-annular recess 65 in the other semi-cylindrical member to provide an annular recess adapted to receive an outwardly extending annular rib 60 formed integrally with each cylinder head and surrounding an opening 61 provided in the latter. The packing gland 56 will therefore be held in position when the semi-cylindrical members 62 are bolted together in the manner described. It will be understood that the piston rod 8 reciprocates in the opening 61.

A flanged sleeve 64 has a tapered end 80 inserted within the packing gland 56. Packing 66 is disposed about the tapered inserted end of the sleeve 64. Bolts 67 connect the flanged end 55 of the pipe 54 to the flanged sleeve 64 and to the semi-cylindrical members 62 and 62'.

It will be noted that the flanged sleeve 64 can be moved toward the cylinder head by screwing the bolts 67 and that the packing 66 will thereby be compressed.

The cooling fluid from the pipe 54 will pass through the central bore 68 of the piston rod 8 into each piston 9. The latter is formed with an annular passage 69. Channels 70 and 71 connect each end of the annular passage 69 with the central bore 68 of the piston rod 8. The central bore 68 is closed between the communicating channels 70 and 71 by a closure 72 which is integral with the walls of the piston rod 8. Consequently, the cooling fluid is compelled to pass through each of the pistons 9 around the closure 72.

The end of the piston rod 8 is screwed into the elbow member 74 which is integral with the cross member 10. A pipe 75 communicates with the elbow member 74 and extends laterally and then rearwardly. The pipe 75 is slidably disposed within a sleeve or casing 76, a packing gland 77 being provided at the end of the sleeve 76. The sleeve 76 is stationary and the end of the pipe 75 will be reciprocated therein by the movement of the cross head 10 with which the elbow member 74 is connected. A pipe 79 connects with the other end of the sleeve 76 and extends rearwardly. A branch pipe 80 communicates with the pipe 79 and opens into an annular passage 81 which is formed in the wall of the cylinder 4. Likewise, a pipe 82, connecting with the end of the pipe 79, communicates with the annular passage 81 in the wall of the cylinder 3. The annular passages 81 communicate with channels 87 in the cylinder heads 58 and 59 and with channels 88, 89, 90 and 91 in the housing 21.

After circulating through the side walls of the cylinders 3 and 4, the heads of the cylinders 3 and 4, and the housings 21, the cooling fluid passes through a pipe 92 from

the cylinder 3 and a pipe 84 from the cylinder 4 to the pipes 83 and 83' respectively, which connect with the pipe 85. The latter extends to the source of water supply (not shown) and the fluid passing therethrough is again drawn through the intake pipe 53 into the pump 52 for further circulation about the cylinders 3 and 4.

From the foregoing description of the various parts of the device, the operation thereof may be readily understood. Fuel from the carbureter 45 passes through the intake manifold 23 into the combustion chamber 27. The gases created by the explosion in the combustion chamber expand and reciprocate the pistons 9 in the cylinders 3 and 4. It will of course be understood that valves located at corresponding ends of the cylinders 3 and 4 will be operated simultaneously and that the pistons will consequently be reciprocated at the same time in the same direction.

The effective means for cooling the pistons and associated parts in a device embodying my invention, renders the device effective in performing the functions for which an engine of the type described is employed.

Air chambers 86 are carried by the pipes 54 and 80, respectively, as shown in the drawing, and serve to reduce the noise occasioned by the rush of the cooling fluid through the fluid conducting passages.

The packing gland construction shown in the accompanying drawings and described in the foregoing specification has been made the subject of a concurrent application, Serial No. 382,139 filed May 17, 1920, and it is not my intention to claim the packing gland feature *per se* in the present application.

I claim:

1. In an internal combustion engine, a pair of horizontally disposed co-axially alined water jacketed cylinders, a hollow piston rod extending through said cylinders and having its ends projecting beyond the opposite ends thereof, a piston for each cylinder, said pistons consisting of sleeve members rigidly mounted on the piston rod and arranged for reciprocation within the cylinders, said pistons each being formed with an annular closed cavity intermediate its inner, outer and end walls, said piston rod also being formed to provide within each cylinder, spaced apart obliquely extending annular passages through its walls communicating with each of said first named annular cavities adjacent the ends thereof and with a plug arranged within its central bore to close the latter intermediate said last named annular passages, a tubular liquid conducting member connecting with said piston rod at the outlet end thereof to move therewith,
2. In an internal combustion engine, a pair of horizontally disposed co-axially alined water jacketed cylinders, a hollow piston rod extending through said cylinders and having its ends projecting beyond the remote ends thereof, a hollow piston rigidly mounted on said piston rod within each cylinder and arranged for reciprocation therein, said piston rod being provided with closures in the portions of its inner bore encompassed by said pistons and with passages communicating with the cavity in each of said pistons and with the piston rod at opposite sides of each of said closures, a hollow cross-head carried by said piston rod at its outlet end, a crank shaft operatively connected with said cross-head, a pump operatively connected with said crank shaft and adapted for connection with a source of cooling fluid supply, a conduit connecting with said pump and formed adjacent its end to receive the inlet end portion of said piston rod, packing means engaging with the relatively moving portions of said piston rod and said conduit for preventing loss of the cooling fluid passing therethrough, a second conduit connecting said hollow cross-head with the water jackets of said cylinders, said last named conduit comprising telescopingly arranged sections having packing means engaging the relatively moving sections thereof to prevent loss of the cooling fluid passing therethrough while permitting free functional movement of the piston rod and the section of the last named conduit joined thereto, and a conduit communicating with said water jackets and adapted for connection with the source of cooling fluid supply.

a coöperating tubular liquid conducting member connecting said cylinders and communicating with said water jackets, said last named tubular member being provided with an open extension adapted to receive the first named tubular member, packing means for preventing loss of the liquid passing from said first named tubular member to the second tubular member while permitting free reciprocating movement of the former within the extension to the latter, a pump adapted for connection with a source of supply of a cooling fluid, a conduit connecting with said pump and formed adjacent its end to receive the reciprocating open inlet end of said piston rod, packing means carried by said conduit at its end for preventing loss of the cooling fluid passing into said piston rod from said conduit, and a conduit communicating with the water jackets of said cylinders and adapted for connection with the source of supply of the cooling fluid.

2. In an internal combustion engine, a pair of horizontally disposed co-axially alined water jacketed cylinders, a hollow piston rod extending through said cylinders and having its ends projecting beyond the remote ends thereof, a hollow piston rigidly mounted on said piston rod within each cylinder and arranged for reciprocation therein, said piston rod being provided with closures in the portions of its inner bore encompassed by said pistons and with passages communicating with the cavity in each of said pistons and with the piston rod at opposite sides of each of said closures, a hollow cross-head carried by said piston rod at its outlet end, a crank shaft operatively connected with said cross-head, a pump operatively connected with said crank shaft and adapted for connection with a source of cooling fluid supply, a conduit connecting with said pump and formed adjacent its end to receive the inlet end portion of said piston rod, packing means engaging with the relatively moving portions of said piston rod and said conduit for preventing loss of the cooling fluid passing therethrough, a second conduit connecting said hollow cross-head with the water jackets of said cylinders, said last named conduit comprising telescopingly arranged sections having packing means engaging the relatively moving sections thereof to prevent loss of the cooling fluid passing therethrough while permitting free functional movement of the piston rod and the section of the last named conduit joined thereto, and a conduit communicating with said water jackets and adapted for connection with the source of cooling fluid supply.

LANSON B. JOYNER.
